UNITED STATES, PATENT OFFICE

ISAAC HARTER, OF DONGAN HILLS, NEW YORK, ASSIGNOR TO THE BABCOCK & WILCOX COMPANY, OF BAYONNE, NEW JERSEY, A CORPORATION OF NEW JERSEY

ECONOMIZER

Application filed February 12, 1927; Serial No. 167,814. Renewed March 5, 1931.

This invention relates to an economizer that has U-tubes or return bend tubes that are connected to headers and will be understood from the description in connection with the accompanying drawings, in which Fig. 1 is a vertical section through the device; Fig. 2 is a section along the line 2—2 of Fig. 1; Fig. 3 is an end view on an enlarged scale showing one of the details; Fig. 4 is a view similar to Fig. 3 showing a modification; Fig. 5 is a sectional view similar to Fig. 1 but on an enlarged scale and partly broken away, also showing how one of the tubes can be replaced; Fig. 6 is a section along the line 6—6 of Fig. 5 and Fig. 7 is a section along the line 7—7 of Fig. 5.

In the drawings, reference character 1 indicates headers that are in the illustrative embodiment of the invention square in cross section and placed one above the other in a single row along one side of the gas passage or conduit for waste products of combustion from a boiler furnace. The headers 1 are each provided with two rows of holes on one side, the holes in each row being staggered with respect to the holes in the other row, with the end of the upper row extending beyond the end of the lower row at one end of the header, and the end of the lower row extending beyond the end of the upper row at the other end of the header. The headers 1 are connected by means of the return bend tubes that have legs 2 and 3 and return bend portions 4. These tubes extend from the upper row of holes in one header to the lower row of holes in the next header above, with the return bends 4 all in parallel planes that extend at an angle of about 45° to the gas stream.

A support 6 preferably in the form of a perforated plate is placed between the headers 1 and the return bends 4 and is provided with rows of holes corresponding to the rows of holes in the headers. The tubes extend through these holes and as shown in Fig. 3, rows of holes 7 and 8 for the upper legs 2 and lower legs 3, respectively, of the tubes are so spaced that the upper legs 2 are concentric with the holes 7 and the lower legs 3 rest upon the lower edges of the holes 8. The holes in

the support 6 are made slightly larger than the outside diameter of the tubes. In the modification shown in Fig. 4, the plate 6' is provided with rows of holes 7' and 8' corresponding to the holes in the headers 1. The holes 8' are made elongated, and the upper legs 2, as well as the lower legs 3 of the tubes, rest upon the bottom edges of the holes 7' and 8', respectively.

The headers 1 may be installed slight distances apart and maintained in these positions, with the distance between a hole in one header and a hole in an adjacent header, that are connected by a tube, slightly more than the diameter of the return bend portion 4 of the tube, so that the legs 2 and 3 of the tubes will approach each other toward the bend, thus enabling the economizer to be drained. Rows of holes in the header are spaced apart sufficient distances to provide lanes 10 between the upper legs 2 of one row of tubes and the lower legs 3 of the next row of tubes.

The tubes are supported near their return bends upon cross bars 11, whose ends rest in slots 12 (Figs. 5, 6 and 7) in the channels 13 on opposite sides of the economizer. A plate 14 is attached to each bar 11 so that its upper edge extends slightly above the upper edge of the bar and semicircular recesses or notches 15 are provided in these plates, in which notches the legs 2 of the tubes rest to keep the tubes spaced apart the proper distances.

This invention is especially useful where economizers are installed in places that make it impossible to withdraw the tubes longitudinal distances equal to their entire lengths on account of obstructions being present. By the present invention tubes can be withdrawn by moving them merely sufficient distances to cause their free ends to clear the support 6, then turning the tubes through an angle and then removing them sidewise through the lanes 10. In order to do this even with the width of the lanes less than the diameter of the tubes, the return bend portions of a row of tubes above the one that is to be taken out are sprung upwardly. This may be done, for example, by providing turn-

buckles 16 near the ends of the supports 11 and extending from one support to the second one below as most clearly shown in Figs. 5 and 6. The supports 11 are preferably installed so that alternate ones will be staggered with respect to each other, as shown in Fig. 5. By means of the turn-buckles 16, a row of tubes may be sprung upwardly to the positions shown in the broken lines in Figs. 5 and 6, thus leaving room between the lower legs of these tubes and the upper legs of the lower row of tubes for a tube to be withdrawn sidewise, as shown by broken lines in Figs. 5 and 6. The bar 11 and spacing strip 14 are removed from the row of tubes of the one that is to be taken out. The tube that is to be removed is disconnected from the headers and is moved longitudinally until its free ends pass out of the holes in the support 6, after which the tube is maneuvered into the lane and in so doing the tube is turned until its legs are in a horizontal plane, and then it is moved sidewise through the lane 10 which has been enlarged, as explained above, by springing the return bend ends of the upper row of tubes upwardly. A new tube is then maneuvered into place from which the injured tube was removed, and its ends expanded into the headers, after which the sagging bent ends of the corresponding row of tubes are lifted a sufficient distance to enable the bar 11 and spacing strip 14 to be replaced. This may be done, for example, by inserting a service bar 35 through the bent ends of the tubes and through the slots 12' and then lifting upwardly on this service bar by means of a turn-buckle similar to that above described. After the bar 11 and spacing strip 14 have been replaced, the turn-buckle is removed and the service bar withdrawn, whereupon the upper sides of the tubes 2 drop into the notches 15 on the spacing strip 14.

When the tubes extend through the plate 6 as shown in Fig. 3, the bent ends of the tubes can be raised slightly farther after the upper sides of the legs 2 come into contact with the upper edges of the holes 7 before the upper sides of the legs 3 contact with the upper edges of the holes 8. In the modification shown in Fig. 4 the distance through which the bent ends of the tubes can be raised before the upper sides of the lower legs 3 come into contact with the plate 6 is considerably greater than in Fig. 3. The slots 8' do not seriously weaken the plate support 6 and their presence avoids the necessity of giving the lower legs 3 of the tubes comparatively sharp bends at the plate 6 when the bent ends 4 of the tubes are raised.

While I have shown and described the invention as applied to an economizer, to which it is particularly adapted, nevertheless it is to be understood that it is capable of use with any other heat exchange device as well.

I claim:

1. In a heat exchange device, return bend tubes connected together with the return bends in parallel planes, a supporting plate between the connections and the return bends through which plate said tubes extend, removable supports for said tubes near said return bends, said tubes being arranged in rows with lanes between said rows through which tubes can be withdrawn and replaced 75 sidewise.

2. In a heat exchange device, return bend tubes connected together with the return bends in parallel planes, a supporting plate between the connections and the return bends 80 through which plate said tubes extend, said tubes being arranged in rows movable with respect to each other and with the upper edge of one row spaced from the lower edge of the next higher row less than the diameter 85 of the tubes but with lanes between said rows through which tubes can be withdrawn and replaced sidewise on the other side of said plate from said headers after moving said rows apart. 90

3. In a heat exchange device, return bend tubes connected together with the return bends in parallel planes, a supporting plate between the connections and the return bends 95 through which plate said tubes extend, said tubes being arranged in single rows with a lane between each two adjacent rows through which tubes can be withdrawn and replaced sidewise, the openings in said plate through which said tubes extend being larger than 100 said tubes.

4. In a heat exchange device, headers each provided with two rows of holes staggered with respect to each other, and single rows of return bend tubes connecting said headers so as to have a lane between the legs of tubes that are connected to each header whereby said tubes may be removed sidewise and supports for said tubes near the return bends and at an intermediate point. 105

5. In a heat exchange device, headers each provided with two rows of holes staggered with respect to each other, and single rows of return bend tubes connecting said headers so as to have a lane between the legs of tubes that are connected to each header whereby said tubes may be removed sidewise and spacing means for said tubes near the return bends. 115

6. In a heat exchange device, headers each provided with two rows of holes staggered with respect to each other, and rows of return bend tubes connecting said headers so as to have a lane between the legs of tubes that are connected to each header whereby said tubes may be removed sidewise, and means for enlarging said lanes toward the return bends. 120

7. In a heat exchange device, headers each provided with two rows of holes staggered with respect to each other, and rows of return bend tubes connecting said headers so as to 125

have a lane between the legs of tubes that are connected to each header whereby said tubes may be removed sidewise, and means for springing the return bend ends of one row

5 of tubes away from an adjacent row.

8. In a heat exchange device, headers each provided with two rows of holes staggered with respect to each other, rows of return bend tubes connecting said headers so as to

10 have a lane between the legs of tubes that are connected to each header whereby said tubes may be removed sidewise, means to support

15 said tubes adjacent the return bends, and means to move said support in order to increase the distance between said tubes and those adjacent thereto.

9. In a heat exchange device, a plurality of rows of return bend tubes disposed with the return bends in each row in substantially

20 parallel planes, means connecting the tubes in one row with the tubes in an adjacent row, said rows being spaced apart to form a lane between them for the passage of a tube therethrough, and means supporting said tubes

25 and constructed and arranged to permit said passage of a tube through said lane.

10. In a heat exchange device, a plurality of rows of return bend tubes disposed with the return bends in each row in substantially

30 parallel planes, means connecting the tubes in one row with the tubes in an adjacent row, said rows being spaced apart to form a lane between them for the passage of a tube therethrough, and removable means supporting

35 said tubes and constructed and arranged to permit said passage of a tube through said lane.

11. In a heat exchange device, a plurality of rows of return bend tubes disposed with the return bends in each row in substantially

40 parallel planes, means connecting the tubes in one row with the tubes in an adjacent row, said rows being spaced apart to form a lane between them, and means supporting said

45 tubes and constructed and arranged so that the tubes in one row may be sprung away from an adjacent row to form a lane wide enough for the passage of a tube therethrough and so that a tube may be thus passed

50 through said lane.

ISAAC HARTER.
